ELECTRONIC FLOOR LEVELER FOR
ELEVATORS

Werner Muller, New York, N. Y., assignor to
Brujac Electronic Corporation, New York, N. Y.,
a corporation of New York

Application September 29, 1944, Serial No. 556,337

11 Claims. (Cl. 187—29)

The present invention relates to the art of automatic elevator control, and, more particularly, to an electronic floor leveler for elevators, and the like.

It is an object of the present invention to provide improved control of elevator operation including stopping the elevator car at the exact level of one of the landings.

It is another object of the present invention to provide a novel and improved device for controlling the raising and lowering of the elevator car whereby upon arrival of the car in proximity to one of the landings, the car is automatically displaced in the upward or downward direction until it has been brought to the exact landing level.

It is a further object of the invention to provide an electronic control device for automatic floor leveling of elevators including a transmitter of high-frequency energy and a pair of receivers for such energy adapted to be selectively actuated for causing upward or downwards operation of the driver motor until a balanced condition and exact leveling of the elevator car are obtained.

It is also within the contemplation of the invention to provide an electronic floor leveler system for elevators, and the like, in which radio-frequency transmitting and receiving means are arranged in the elevator car, said means being adapted to cooperate with stationary means arranged in the elevator shaft, causing transfer of radio-frequency energy from the transmitter to one of the receivers in accordance with the relative position of the car with respect to the landing.

The invention also contemplates an electronic elevator floor leveler based upon the selective transmission of impulses from a radio-frequency transmitter to a pair of receivers by means of stationary capacitive elements arranged in proximity to each of the landings, which is very simple in construction, satisfactory and foolproof in its operation, and which may be readily manufactured and employed on a practical and industrial scale at a low cost.

Other and further objects and advantages of the invention will become apparent from the following description, taken in conjunction with the accompanying drawings; in which

Fig. 1 illustrates a side elevational view, having parts in section, of an electronic floor leveler system embodying the principles of the present invention.

Fig. 2 depicts a similar elevational view, some-

what fragmentary in character, of the control box including the electronic equipment of the system together with its capacitive control electrodes;

5 Fig. 3 shows a sectional view on line 3—3 of Fig. 2 through one of the control electrodes with its tuning coil and mechanical adjusting means; and

10 Fig. 4 is a circuit diagram illustrating a preferred form of circuit organization of the electronic control device of the invention.

While a preferred embodiment of the invention is described herein, it is contemplated that considerable variation may be made in the 15 method of procedure and the construction of parts without departing from the spirit of the invention. In the following description and in the claims, parts will be identified by specific names, for convenience, but they are intended to be as 20 generic in their application to similar parts as the art will permit.

Broadly stated, in accordance with the principles of the invention, there is provided in combination with the elevator car a transmitter of

25 radio-frequency energy and a pair of receivers for such energy, said transmitter and receivers being displaced in the elevator shaft concurrently with the displacement of the elevator car. The transmitter and the receivers are operatively as-

30 sociated with coupling elements which are arranged in close proximity to one of the sides of the shaft and are adapted to cooperate with stationary coupling elements mounted in the shaft at each landing. Upon approach of the elevator car to one of the said landings, the stationary coupling element will become effective to trans-

35 fer radio-frequency energy from the transmitter to one of the two receivers in accordance with the momentary position of the elevator car with respect to such landing.

40 In accordance with the receiver energized, suitable control or switching means become effective, causing the driver motor to move the car in the upward or downward direction until a balanced condition is obtained in

45 which the elevator car is stopped. Generally speaking it is preferred to employ the automatic floor leveler of the invention in combination with manually operable control elements for the driver motor. These control elements are automatical-

50 ly disabled when the car approaches one of the landings and leave the car to the sole control of the floor leveler equipment.

Referring now more particularly to the drawings, the mechanical construction and arrangement of the automatic floor leveler of the inven-

tion will be best understood by reference to Figs. 1 and 2 of the drawings. Reference character 10 denotes the top of the elevator car upon which there is mounted a bracket 11 by means of nuts 12. To this bracket there is secured a control box generally denoted by reference character 13, preferably made of metal, housing the elements of the electronic circuits constituting the control system. The control box is covered by means of a metal cover plate 14 which provides mechanical protection and at the same time electrostatic shielding for the electronic circuits. Cover plate 14 is provided with three circular openings 15, 16 and 17, (Fig. 2) through which there are exposed control electrode plates 18, 19, and 20, respectively. Of these, the center one is operatively associated with the transmitter of radio-frequency energy while the upper and lower ones are respectively associated with two receivers for such energy. These control plates are arranged for cooperation with a stationary control member or plate 21 provided in the form of an elongated metal plate having a pin 22 secured to each end thereof, said pins being slidably mounted in insulative bosses 23 provided on one side 24 of the walls of the elevator shaft. Coil springs 25 around pins 22 between boss 23 and plate 21 resiliently hold the said control plate in a position in which it is closely spaced to plate 14 of the control box without, however, touching the same. It will be noted that stationary control plate 21 is capable of slight displacement against the pressure of the springs in the event that plate 14 would strike against the same during their relative displacement. Preferably, control plate 21 is fully covered by means of a suitable insulating material 26, such as Bakelite, Textolite, and the like. A readily yielding elastic member or bumper 27 constituted of sponge rubber, or the like, may be provided at either end of the said plate to prevent mechanical shock of the control plate by accidental contact thereof with cover plate 14 of the control box and at the same time remove dirt or dust, which may accumulate on the surface of the cover plate during the operation of the device. Openings 15, 16 and 17 in cover plate 14 of the control box may be covered by a thin sheet or plate of insulating material (not shown), if desired, to prevent the entrance of dust into the box without interfering with the capacitive cooperation of control electrode plates 18, 19 and 20 with stationary plate 21. The relative position of stationary control plate 21 with respect to door 28, and that of control box 13 with respect to elevator car 10 are so determined that when the said control plate is symmetrically positioned with respect to the control box and to the three control electrodes 18, 19, and 20 therein, door 28 of the shaft is accurately aligned with the door of the car.

The electronic circuits forming part of the control device of the invention will be best understood from Fig. 4. These circuits are energized from the direct or alternating current power line connected to terminals 30. A switch 31 is inserted in one of the leads connected to plates 32 of a rectifier tube 33 and is also grounded through a small by-pass condenser 34. Cathodes 35 of the rectifier tube are connected through filter resistances 36 and 37 to point 38, which constitutes the B plus terminal of the power pack. Filter condensers 39, 40 and 41 are connected between cathodes 35, the common terminals of resistances 36 and 37, B plus terminal 38, and ground, respectively.

The radio-frequency transmitter is built around

a screen-grid tube 42, cathode 43 of which is grounded. Control grid 44 of the said tube is connected through a tuning condenser 45 and a tuning coil 46 to ground, while its screen grid 47 is connected through a coupling coil 48 to B plus terminal 38. Coils 46 and 48 are coupled to each other and constitute a high-frequency transformer 49. Plate 50 is connected to the B plus terminal through a coil 51 and through coil 48. The radio-frequency oscillatory energy is withdrawn at the plate and is applied to capacitor electrode 19 through a coupling condenser 52.

Receiver 1 includes a radio-frequency amplifier tube 60 of the screen-grid type having a control grid 61, which is directly connected to capacitor plate 18. A tuning coil 62 is connected between the said grid and ground and is so dimensioned as to be resonant to the radio-frequency oscillations produced by the transmitter. Cathode 63 is grounded through a biasing resistor 64 having a by-pass condenser 65 connected across the same. Screen-grid 66 is connected to the B plus terminal 38.

Tube 60 is coupled to detector tube 67 by means of a high-frequency transformer 68, having a tuned primary circuit 69 and a tuned secondary circuit 70. Tuned circuit 69 is connected between plate 71 of tube 61 and B plus, while tuned circuit 70 is connected between grid 72 of tube 67 and ground. Of course, the said tuned circuits are inductively coupled with each other, such coupling being supplemented by means of a coupling condenser 73, establishing direct capacitive connection between the plate of the amplifier tube and the grid of the detector tube. Cathode 74 of the detector tube is connected to ground through biasing resistance 75 having a by-pass condenser 76 connected across the same. Plate 77 of the said tube is connected to B plus through operating coil 78 of a relay 79, and a condenser 80 is connected between plate 77 and ground for bypassing the high-frequency oscillations.

Receiver 2 is identical in its circuit arrangement with receiver 1 and similar reference characters 60' to 80' have been employed to denote parts corresponding to elements 60 to 80 of receiver 1. It will be noted that capacitor plate 20 is connected to grid 61' of tube 60' and that operating coil 78' of relay 79' is connected to plate 77' of detector tube 67' and B plus. Tube 61' is jointly biased with tube 67 of receiver 1 by means of cathode resistance 75.

Relay 79 is provided with a pair of normally open contacts 81 and 82 and relay 79' is provided with a pair of similar normally open contacts 81' and 82'. The said contacts are operatively associated with a differential relay 96 having a pair of windings 83 and 83'. Contacts 82 and 82' of relays 79 and 79' are connected to B plus, while contacts 81 and 81' of the same relays are respectively connected to one end of coils 83 and 83' of the differential relay. The other ends of coils 83 and 83' are jointly connected to ground. The coils of the differential relay are adapted to attract one end of an armature 84 pivotally mounted in its center, the said armature being turned clockwise and anti-clockwise according to whether coil 83' or coil 83 of the relay is energized. Armature 84 is mechanically connected with a pair of switching arms 85 and 86 of which 85 is capable of selective cooperation with contacts 87 and 88 and 86 is capable of similar cooperation with contacts 89 and 90 in the deflected positions of the armature, while in the illustrated center position of the armature, the switching arms

are disconnected from all of the contacts. Switching arms 85 and 86 are connected to the two ends of field coil 91 of the driver electromotor and contacts 87 and 90 are connected together and to terminal 92 of the power line. Contacts 88 and 89 are likewise connected together and to one end of armature winding 94 of the motor, the other end of which is connected to terminal 93 of the power line.

From the foregoing description, the operation of the electronic floor leveler of the invention will be readily understood by those skilled in the art. It is to be observed at the outset that all of the tubes forming part of the transmitter and receivers described in the foregoing are provided with conventional heaters for heating their cathodes to electron-emitting operating temperatures and that the wiring of the said heaters has been omitted from the circuit diagram in view of its conventional character. It will be also noted that the transmitter is shown as a conventional electron-coupled oscillator which is producing radio-frequency oscillations in a manner well understood. Preferably, the transmitter is tuned to an operating frequency of about 100 to 300 kilocycles although, of course, other suitable radio-frequencies may be employed with equal or similar results. It may be likewise assumed that driving motor 91, 94 of the elevator may be also energized from other switching means independent from differential relay 96 to cause displacement of the elevator car between the several floors, such switching means being disabled upon the car approaching the landing where the car is to be stopped so that from that point on the car and its driving motor are solely under the control of differential relay 96.

Assuming now that the elevator car is being raised, control box 13 with capacitor plates 18, 19 and 20 will be raised therewith and will arrive in a position in which capacitor plate 18 connected to receiver 1 and capacitor plate 19 connected to the transmitter will arrive into a closely spaced position with respect to stationary capacitor plate 21, while capacitor plate 20 connected to receiver 2 will be still at some distance from the stationary plate. Plates 18 and 19 will be coupled to each other by means of the stationary plate so that radio-frequency energy will be transferred from the transmitter to receiver 1. The received signal will be amplified by tube 60 and rectified or detected by tube 67 so that relay 79 will be energized and its contacts 81 and 82 will be closed. This in turn will close the circuit of coil 83 of differential relay 96 so that its armature 84 will be turned in the anti-clockwise direction, transferring switching arms 85 and 86 from their open center position into their upper position in which they respectively make with contacts 87 and 89. This will close the circuit of motor 91, 94, such circuit being from terminal 92 of the power line, through contact 87, switching arm 85, field coil 91, switching arm 86, contact 89, armature 94, and to the other terminal 93 of the power line. In this position of the differential relay, the motor will be energized to further raise the elevator car. This displacement will be continued until such time as all three capacitor plates 18, 19 and 20 arrive into cooperating position with stationary capacitor plate 21. Radio-frequency energy from the transmitter will now be transferred to both receivers 1 and 2 so that both relays 79 and 79' and both windings 83 and 83' of the differential relay will be energized. Simultaneous operation of the two coils

of the differential relay will bring armature 84 into its neutral or center position in which switching arms 85 and 86 are disconnected from the contacts, thus disabling the driving motor so that the elevator car will be stopped at the exact landing position in which door 28 of the shaft is aligned with the door of the car.

Substantially the same operative sequence occurs when the elevator car is lowered. In this case, capacitor plates 20 and 19, respectively connected to receiver 2 and to the transmitter, will first arrive into cooperating position with stationary capacitor plate 21. Radio-frequency energy will be transferred from capacitor plate 19 to capacitor plate 20, such energy, being amplified and detected in receiver 2, will energize relay 79'. This relay will close its contacts 81' and 82' and will complete the circuit of coil 83' of the differential relay. Armature 84 of the said relay will be displaced in the clockwise direction transferring switching arms 85 and 86 into their lower position in which they make with contacts 88 and 90, respectively, and thus close the circuit of motor 91, 94. The motor circuit will now be from terminal 92 of the power line, through contact 90, switching arm 86, field coil 91, switching arm 85, contact 88, armature 94, and back to the other terminal 93 of the power line. It will be noted that in this case the field coil of the motor will be energized in a direction opposite to that when relay 79 is energized, so that the elevator car will be further lowered. This will continue until all capacitor plates 20, 19 and 18 will be brought into cooperating position with stationary plate 21, when both relays 79 and 79' will be energized and the differential relay will be returned into its neutral position, stopping further rotation of the motor.

It is preferred to provide for adjustment of capacitor plates 18, 19 and 20 in order to bring them to the desired distance from stationary capacitor plate 21 in the operative position of the plates. This adjustment may be accomplished, for example, by means of the structure illustrated in Fig. 3. A metal shield can 100 having a center opening 101 therein is secured to cover plate 14 of control box 13 by means of nuts and bolts 102 so as to cover opening 15. A circular insulating plate 103 having an internally threaded metal bushing 104 in the center thereof is secured by rivets 105 to shield can 100 to cover opening 101. Rivets 105 also hold a pair of light brackets 106, supporting cylindrical coil form 107 with coil 62 thereon. In bushing 104 there is inserted the lower threaded end of a metal rod 108 bearing capacitor plate 18 at its upper end. A screwdriver slot 109 in rod 108 facilitates rotation of the rod, whereby the position of the capacitor plate with respect to cover plate 14 may be accurately adjusted and thus the desired operating conditions obtained. One end of coil 62 is connected to capacitor plate 18 by means of a flexible cable 110 soldered to rod 108 at 111, said cable being long enough to permit rotation of the plate 18 to the extent of a few revolutions. The other end of coil 62 is connected to flexible cable 112, which is passed through opening 113 provided in shield can 100 for this purpose.

Although the present invention has been described in connection with a preferred embodiment thereof, variations and modifications may be resorted to by those skilled in the art without departing from the principles of the present invention. Thus, while the operation of the present embodiment of the invention is based upon the

cooperation of capacitive coupling means, such as displaceable and stationary capacitor plates, in predetermined positions of the elevator car, inductive coupling means may be employed with equal or similar results. Numerous variations are also possible in the circuit organization of the transmitter, of the receiver, and of the switching means for the driving motor. All of these variations and modifications are considered to be within the true spirit and scope of the present invention, as disclosed in the foregoing description and defined by the appended claims.

What is claimed is:

1. An elevator control system which comprises in combination a displaceable transmitting coupling element and a pair of displaceable receiving coupling elements mounted on an elevator car for joint displacement therewith, a source of radio-frequency energy connected to said transmitting element, a pair of receivers for such energy respectively connected to said receiving elements, stationary coupling elements for selective cooperation with said transmitting element and at least one of said receiving elements, and means under the control of said receivers to energize driving means for the car in accordance with the relative position of said displaceable coupling elements with respect to said stationary coupling element.

2. An elevator control system which comprises in combination a displaceable transmitting coupling member and a pair of displaceable receiving coupling members mounted on an elevator car for joint displacement therewith, said receiving members being spacedly disposed with respect to each other in the direction of the elevator travel and having said transmitting member therebetween, a radio-frequency oscillator of substantially constant frequency connected to said transmitting member, a pair of receivers tuned to such frequency respectively connected to said receiving members, a stationary coupling member for selective cooperation with said transmitting member and at least one of said receiving members to transfer oscillatory energy from said oscillator to one of said receivers, and driving means for said car under control of the output of said receivers to displace the car until balanced amounts of oscillatory energy are received by both receivers.

3. An elevator control system which comprises in combination a displaceable transmitting capacitor plate and a pair of displaceable receiving capacitor plates insulatedly mounted on an elevator car for joint displacement therewith, said receiving plates being spacedly disposed with respect to each other in the line of travel of said car and having the transmitting plate therebetween, a radio-frequency oscillator of substantially constant frequency energizing said transmitting plate, a pair of receivers tuned to such frequency respectively connected to said receiving plates, a stationary capacitor plate adapted to couple at least one of said receiving plates to said transmitting plate during the travel of said car and thereby to impress a signal upon the receiver associated with said receiving plate, driving means for said car, and control means for said driving means operable by the output of said receivers to actuate the driving means in one direction when a signal is impressed upon one of said receivers and to actuate the driving means in the opposite direction when a signal is impressed upon the other one of said receivers.

4. An elevator control system which comprises in combination three displaceable capacitor plates spacedly and insulatedly mounted on an elevator car in the line of travel thereof, a radio-frequency transmitter connected to the center one of said plates, a receiver connected to each of the other two of said plates, an elongated stationary capacitor plate mounted in the elevator shaft constructed and arranged for spaced capacitive operation with said displaceable plates in predetermined positions of said car in the shaft to transfer a signal from said transmitter to at least one of said receivers, driving means for said car, and control means for said driving means operable by the output of said receivers to actuate the driving means in one direction when a signal is impressed upon one of said receivers, to actuate the driving means in the opposite direction when a signal is impressed upon the other of said receivers, and to disable said driving means when a signal is impressed upon both of said receivers.

5. An elevator control system which comprises in combination three displaceable capacitor plates insulatedly mounted in uniformly spaced relation on an elevator car in the line of travel thereof, a radio-frequency oscillator connected to the center one of said plates and a receiver connected to each of the other two of said plates, an elongated stationary capacitor plate mounted in the elevator shaft in proximity to each landing in substantially parallel-spaced position with said displaceable plates adapted to capacitively couple said oscillator to at least one of said receivers upon approach of the car to the landing from either direction, a driving motor for said car, and control means for said motor differentially operable by the output of said receivers to cause displacement of the car and of the capacitor plates thereon until substantially balanced signals are impressed upon both receivers and to stop the motor when such balanced condition is obtained.

6. An elevator control system which comprises in combination three displaceable capacitor plates insulatedly mounted in uniformly spaced relation on an elevator car in the line of travel thereof, a radio-frequency oscillator connected to the center one of said plates and a receiver connected to each of the other two of said plates, an elongated stationary capacitor plate mounted in the elevator shaft in proximity to each landing to establish selective capacitive coupling between the oscillator and one of the receivers in accordance with the direction of approach of the car to said landing and to establish such coupling between the oscillator and both receivers in the exact landing position of the car, driving means for said car, and control means for said driving means operable by the output of said receivers to displace the car towards the position in which the stationary plate couples both receivers to the oscillator and to disable the driving means when such position has been obtained.

7. An elevator control system which comprises in combination three traveling capacitor plates insulatedly mounted in spaced relation on an elevator car in the line of travel thereof and facing one of the walls of the elevator shaft, an oscillator connected to the center one of said plates and a receiver responsive to the output of said oscillator connected to each of the other two plates, an elongated stationary capacitor plate insulatedly mounted in the shaft in proximity to each landing arranged for parallel-spaced cooperation with said traveling plates to establish selective capacitive coupling between the oscillator and the receiver associated with the traveling plate facing the wall of the elevator shaft.

8. An elevator control system which comprises in combination three traveling capacitor plates insulatedly mounted in spaced relation on an elevator car in the line of travel thereof and facing one of the walls of the elevator shaft, an oscillator connected to the center one of said plates and a receiver responsive to the output of said oscillator connected to each of the other two plates, an elongated stationary capacitor plate insulatedly mounted in the shaft in proximity to each landing arranged for parallel-spaced cooperation with said traveling plates to establish selective capacitive coupling between the oscillator and the receiver associated with the traveling plate facing the wall of the elevator shaft.

lator and one of the receivers in accordance with the direction of approach of the car to said landing and to establish such coupling between the oscillator and both receivers in the exact landing position, means for adjusting the relative position of said stationary and traveling capacitor plates, driving means for said car, and control means for said driving means operable by the output of said receivers to displace the car towards the position in which the stationary plate couples both receivers to the oscillator and to disable the driving means when such position has been obtained.

8. The elevator control system claimed in claim 7 wherein the stationary capacitor plate is resiliently mounted.

9. The elevator control system claimed in claim 7 wherein the stationary capacitor plate is covered with an insulative layer.

10. In an automatic floor leveler for elevators, and the like, having driving means for the elevator car and control means for said driving means, the improvement which comprises a transmitter and a pair of receivers of radio-frequency energy in said car, coupling elements on said car and at each landing in the elevator shaft adapted to cooperate with each other upon approach of the car to a landing to selectively couple the

transmitter to one of the receivers in accordance with the direction of such approach and to both of the receivers in the landing position, and means responsive to the output of the said receivers to differentially actuate the said control means for displacement of the car towards the nearest landing position and to disable the driving means in said position.

11. In an automatic floor leveler for elevators, and the like, having driving means for the elevator car and control means for said driving means, the improvement which comprises a generator of constant-frequency oscillations and a pair of receivers for such oscillations in said car, a plurality of capacitor plates on said car and a capacitor plate in the elevator shaft at each landing, said plates being adapted to cooperate with each other upon approach of the car to a landing to selectively couple the generator to one of the receivers in accordance with the direction of such approach and to both of the receivers in the landing position, and means responsive to the output of said receivers to differentially actuate the said control means for displacing the car towards the nearest landing position and to disable the driving means when the landing position has been obtained.

WERNER MULLER.
